Des. 185,053
Patented Apr. 28, 1959

185,053

DISPENSER FOR SHEET MATERIAL

Harold Warp, Chicago, Ill., assignor to Flex-O-Glass, Inc.,
a corporation of Illinois

Application October 31, 1957, Serial No. 48,288

Term of patent 14 years

(Cl. D4—3)

Fig. 1 is a perspective view of a dispenser for sheet material embodying the new design;

Fig. 2 is an end elevational view thereof;

Fig. 3 is a front elevational view thereof; and,

Fig. 4 is a top plan view thereof.

I claim:

The ornamental design for a dispenser for sheet material, as shown.
